UNITED STATES PATENT OFFICE.

THOMAS J. FEGLY AND GEORGE O. LEOPOLD, OF PHILADELPHIA, PENNSYLVANIA,
ASSIGNORS TO NORTH BROS. MFG. CO., OF PHILADELPHIA, PENNSYLVANIA, A
CORPORATION OF PENNSYLVANIA.

CHUCK FOR EXTENSION BITS.

Application filed November 25, 1925. Serial No. 71,445.

The object of our invention is to construct a chuck for extension bits that can be made very compact and strong, and which will accommodate bits having different lengths of 5 tapered heads.

In the accompanying drawing:

Fig. 1 is a side view of an extension bit illustrating my improved chuck;

Fig. 2 is a longitudinal sectional view 10 showing a bit having a small head secured to the extension bit by the chuck;

Fig. 3 is an end view showing a small bit 15 in position in the chuck;

Figs. 4, and 5 are views similar to Figs. 2 and 3, showing a large bit in the chuck; and

Fig. 6 is a perspective view showing the parts of the chuck detached.

The extension bit 1 has the usual spindle 20 2 and tapered head 2^a, rectangular in cross-section. This spindle 2 may be of any length desired.

The body portion 3 of the chuck 4 is secured to the spindle 2 of the extension bit 25 1 by a transverse pin 5 in the present instance, and has a flat tongue 6 projecting at its opposite end. This tongue fits a slot 7 in a socket portion 8 of the chuck, so that while the socket portion has a limited longitudinal 30 movement, it must turn with the body portion, and with the extension bit located between the end of the body portion 3 and the socket portion 8, there is a spring 9, which tends to force the socket portion away from 35 the body portion.

A casing 10 encloses the parts of the chuck, and is reduced to form a shoulder 11. The extension 12 reduced to form the shoulder has a rectangular opening therein, to 40 allow for the passage of the rectangular head 13 of a bit 14.

On the extension bit back of the body 3 of the chuck is a loose adjusting sleeve 15, which is held against longitudinal movement 45 by a split ring 16 located in a groove in the extension bit. At one end of the adjusting sleeve 15 is a screw-thread 17, adapted to an internal thread on the casing 10. The balance of the sleeve 15 is knurled to 50 provide a handhold.

On the outer end of the tongue 6 of the body portion 3 is an abutment 18 in the form of a headed-screw. This screw acts as an abutment for the end of a bit and also retains

the socket portion 8 to the body portion 55 when the casing is removed.

In the casing is a bayonet-slot 19, into which extends a pin 20 screwed into the body portion 3. When the pin 20 is in the transverse portion 21 of the slot 19, the 60 rectangular opening in the socket portion 8 is in alignment with the rectangular opening in the end of the casing 10.

When the casing 10 is turned to bring the pin 20 in alignment with the longitudinal 65 portion 22 of the slot 19, then the rectangular opening in the socket is out of alignment with the rectangular opening in the casing, and by turning the adjusting sleeve, the casing is moved longitudinally, and locks the 70 casing from turning while the pin is in the longitudinal portion of the slot.

A chuck made in accordance with our invention can enter comparatively small holes formed by the auger bit. The diameter of 75 the casing is the limit as there are no parts projecting laterally beyond the casing.

The operation is as follows:

When the casing is in the position shown in Fig. 1, the rectangular opening in the 80 socket portion 8 of the chuck is in alignment with the rectangular opening in the casing, and the head 13 of the bit 14 can be inserted in the chuck, the head passing the shoulder 11. The casing 10 is then turned 85 so that the pin 20 is in line with the portion 22 of the bayonet-slot 19. As the socket portion remains stationary, the rectangular opening in the casing is moved out of alignment with the rectangular opening in the 90 socket portion, and the shoulder 11 extends under the head 13 of the bit 14, preventing its withdrawal from the chuck. The adjusting sleeve is turned, moving the casing 10 and the socket portion 8 longitudinally 95 against the pressure of the spring 9 until the end of the head 13 of the bit 14 comes in contact with the abutment 18, clamping the head of the bit between the abutment and the shoulder of the casing. 100

Bits have different lengths of heads, and in order to accommodate these heads, the socket member is allowed a certain amount of longitudinal movement in respect to the body portion of the chuck, the spring 9 105 keeping the socket member in engagement with the head of the bit.

In Figs. 2 and 3 a comparatively short

headed bit is shown, and in Figs. 4 and 5 a long-headed bit is shown.

While the invention is described as particularly adapted to an extension bit, it may be used as a chuck on other tools if desired.

To release a bit, the casing is moved by turning the adjusting sleeve so that the shoulder is withdrawn from the head of the bit. If the tapered head of the bit is jammed 10 in the socket, a blow on the end of the extension bit will release the head.

We claim:

1. The combination in a chuck, of a spindle; a body portion secured to the spindle; 15 a longitudinally movable socket portion arranged to turn with the spindle, said body portion having an abutment extending into the socket of the socket portion; a casing enclosing the body portion and the socket portion, and having a shoulder beyond the socket portion to engage the head of a bit located in the socket; and means for moving the casing longitudinally to clamp the head of a bit against the abutment on the body portion.

2. The combination in a chuck, of an extension bit; a body portion having a tongue; a socket portion shaped to receive a bit and having a slot to receive the tongue of the

body portion; an abutment on the tongue 30 extending into the socket portion; a casing having a shoulder to extend under the head of the bit; and a sleeve on the extension bit and held against longitudinal movement thereon, said sleeve engaging the casing and 35 arranged to be turned to bring the shoulder of the casing in contact with the head of the bit, so as to clamp the head of the bit against the abutment.

3. The combination in a chuck, of a spindle; a body portion secured to the spindle, said body portion having a tongue at its outer end; a socket member having a slot in its inner end to receive the tongue; a spring located between the body portion and the 45 socket member; a screw abutment having a head, said abutment extending into the socket, the head retaining the socket portion to the body portion; a casing having a shoulder at its outer end and a rectangular 50 opening beyond the shoulder; a screw-threaded adjusting sleeve on the spindle back of the body portion; and a split ring on the spindle retaining the sleeve in position, the casing having an internal thread to 55 engage the thread on the adjusting sleeve.
